UNITED STATES PATENT OFFICE

HARRISON R. WILLIAMS, OF GLENS FALLS, NEW YORK

SANITARY TOILET COVER

Application filed June 8, 1928. Serial No. 283,804.

This invention relates to sanitary paper covers for toilet seats and has for an object to provide a cover which will effectively protect the users of the toilet against uncleanliness and against infectious diseases.

5 It is a particular object of the invention to provide a cover of this character which will be automatically carried away by the flushing of the toilet, so that a user of the toilet will 10 not under any circumstances find it necessary to handle a cover left on the seat by a previous user.

To this end the cover desirably comprises a body portion adapted to cover the seat, and 15 a tongue depending within the bowl which tongue is provided with slits in the lower portion thereof to facilitate the drawing of the cover into the bowl when the toilet is flushed.

20 Other objects and advantages will hereinafter appear.

In the drawings forming part of this specification.

Figure 1 is a plan view of a toilet seat 25 cover embodying features of the invention; and

Figure 2 is a side elevation, partly in section showing the cover of Figure 1 applied to the toilet seat.

30 The cover 1 is desirably made of soft, flexible paper of a kind that is readily disintegrable in water and therefore capable of being flushed down the toilet without clogging the soil pipe. The cover comprises a marginal or body portion 2 which is preferably rectangular but may, if desired, have the contour of the toilet seat. The cover material is cut to form the necessary opening therein, the severed material lying inside the bounds 35 of the body portion being left attached at its forward end to the body portion to provide a protective tongue 3 adapted to be folded downward into the toilet bowl. This tongue 3 is provided near the rear or lower end thereof 45 of with zigzag slits in its side margins forming streamers 4 for facilitating the drawing of the cover into the bowl by the water when the toilet is flushed.

It is not desirable that the tongue, which 50 is of absorbent material, dip into the water

in the bowl while the toilet is in use. Neither is it desirable that the user be required to position the tongue in the bowl with any degree of exactness to enable it to be caught and carried down by the water, because in such case it would frequently happen that careless persons, failing to take the necessary care in positioning the tongue, would leave the cover on the seat when quitting the toilet, and this would put upon the subsequent user the necessity of handling the old cover in order to dispose of it.

With the construction as described, however, the carrying away of the cover by the water is assured in the most common types of toilets, even though the tongue is carelessly placed. The tongue is made of substantially the full width of the opening in the seat so that the space between the tongue and the front of the bowl is of substantial width. When the toilet is flushed the rushing water apparently exerts an aspirating action sweeping out from the space between the front of the bowl and the tongue, a portion of the air in such space. The width of the tongue prevents the rapid replacement of the withdrawn air, and hence the tongue is drawn or sucked forward toward the front of the bowl and toward the flowing water. The streamers formed on the tongue are readily flexed forward and sucked into the stream of descending water, caught by it, and caused to draw the entire lower end of the tongue into the stream of water so that the entire cover is pulled down forcibly into the bowl. The zig-zag edges of the streamers and of the tongue body serve effectually to prevent separation of the streamers and the tongue from the stream of water, once they have been caught by the water, and to increase the pull which the water may exert upon the cover.

It will be seen that the cover constructed according to the present invention serves both to completely guard the user against contact with the toilet seat, and to assure against the necessity of touching a cover previously used by someone else.

While I have described what I believe to be the best embodiment of my invention, I do not wish to be limited to the embodiments

shown but what I desire to cover by Letters Patent as set forth in the appended claims.

Claims:

1. A sanitary seat cover for toilets consisting of a sheet of flexible paper having a body portion adapted to cover the toilet seat, a protective tongue at the inner front edge of such body portion adapted to extend downward into the toilet bowl, and streamers 10 forming a part of the tongue to be caught by the water when the toilet is flushed for drawing the cover into the bowl.

2. A sanitary seat cover for toilets consisting of a sheet of flexible paper having a body 15 portion, and an integral tongue connected to the body portion at the inner boundary thereof, said tongue being adapted to extend downward into the bowl and having zigzag slits formed in the lower portion thereof to 20 facilitate drawing of the cover into the bowl by the water when the toilet is flushed.

In testimony whereof I have affixed my signature to this specification.

HARRISON R. WILLIAMS.
